CLAIM

The ornamental design for the drip-feed valve, as shown and described.

DESCRIPTION

FIG. 1 is a front elevational view of a drip-feed valve in a closed position showing my new drawing;

FIG. 2 is a sectional view of the drip-feed valve as shown in FIG. 1 in an open position with one part of the valve rotated through 180° relative to the other part; FIG. 3 is a top plan view of the drip-feed valve as shown in FIG. 1 with the two parts including a front section and a rear section being separated from the other;

FIG. 4 is a sectional view of the drip-feed valve as shown in FIG. 1 and taken on line IV—IV;

FIG. 5 is a left end view of the drip-feed valve as shown in FIG. 1;

FIG. 6 is a right end view of the drip-feed valve as shown in FIG. 1;

FIG. 7 is a right end view of the front section of the drip-feed valve as shown separated in FIG. 3;

FIG. 8 is a left end view of the rear section of the drip-feed valve as shown separated in FIG. 3;

FIG. 9 is a front perspective view of the drip-feed valve as shown in FIG. 1; and

FIG. 10 is a rear perspective view of the drip-feed valve as shown in FIG. 1.

FIG.1.

FIG.2.

FIG.3.

FIG.4.

FIG.5.

FIG.6.

FIG.7.

FIG.8.

FIG. 9.

FIG. 10.
